UNITED STATES PATENT OFFICE

GEORGE H. GILMAN, OF BELMONT, MASSACHUSETTS

PERCUSSIVE TOOL

Application filed March 5, 1921, Serial No. 449,667. Renewed September 12, 1929.

My invention relates to fluid pressure operated percussive tools and particularly but not exclusively to hammer rock drills.

My invention will be best understood from the accompanying drawings and following description of a specific embodiment of my invention selected for illustrative purposes, while the scope of my invention will be particularly pointed out in the appended claims.

10 In the drawings:

Figure 1 is a longitudinal section of a plug drill;

Figure 2 is a section on the line 2—2 of Figure 1; and

15 Figure 3 is a section on the line 3—3 of Figure 2 with parts broken away and showing the piston at the end of its stroke opposite that shown by Fig. 1.

The submitted embodiment of my invention comprises a cylinder in which is reciprocably mounted a hammer piston for imparting percussion to a drill steel 1 carried at the forward end of the cylinder, while at the rearward end of the cylinder I provide a handle 2 for supporting the machine.

20 The cylinder comprises a forward member 3 and a rearward member 4, these members respectively having formed therein a forward bore 5 and a smaller rearward bore 6 communicating with the forward bore. The piston is provided with a head 7 fitting the forward bore and a shank 9 fitting the rearward bore while extending forwardly from the head is the hammer bar 10 formed to fit the reduced diameter portion 11 of the cylinder. The shank is provided with a reduced diameter portion 12 near its juncture with the head and in a manner hereinafter described the shank controls the admission of motive 25 fluid to opposite sides of the head.

20 The bore 5 is provided with a portion of enlarged diameter 13 at its rearward end for receiving the forward portion 15 of the member 4, the latter being provided with a flange 45 17 forming a shoulder abutting the rearward end face 19 of the member 3. Rearwardly of the cylinder member 4 is located a head block 21 which is provided with a sleeve 23 surrounding the end of the cylinder, the sleeve 50 being provided with interior screw threads

engaging exterior screw threads on the forward cylinder member as indicated at 25 to hold the parts in assembled relation.

The handle member 2 is provided with a sleeve 29, slidably mounted on the head block 55 and is held in position by the air hose nipple 31 which extends through the slot 33 formed in the sleeve and is threaded into the socket 35 of the head block. Through the head block is formed an axial bore 37, which receives the 60 tubular cushion plug 39. Slidably mounted in the cushion plug is a cylindrical throttle valve 41 provided with a reduced diameter portion 43 adapted when the valve is in its forward position as illustrated by Fig. 1 to 65 establish communication between the intake passage 45 and a passage 47 in communication with the annular groove 49 formed in the rear surface of the head block abutting the rearward end of the cylinder member 4. The 70 axial bore of the head block receiving the cushion plug is enlarged at its forward end to provide a chamber 51 for receiving the head 53 of the plug. This chamber is placed in constant communication with the live air 75 supply by means of a passage 55 for maintaining a constant pressure against the forward surface of the plug and throttle valve. From this it follows when the operator removes the pressure of his hand from the handle, the air in the chamber 51 will move the 80 throttle valve and handle rearwardly and interrupt communication between the passages 45 and 47 and thus stop the hammer from reciprocating. With the handle in the 85 position illustrated by Fig. 1, the air in the chamber 51 acting on the head of the cushion plug and the forward end of the throttle valve absorbs the rearward vibration and thus prevents the same from being transmitted to the hand of the operator.

The bore 6 of the rearward cylinder member is enlarged at 57 and 59 to form spaced annular grooves or chambers which are placed in communication with each other and with the annular groove 49 of the head block by means of one or more intersecting passages 61 drilled through the wall of said member. Intermediate these grooves I provide the radial passage 63 which intersects the bore 6 and is 95 100

in communication with the ports 65 of one or more return passages 67 drilled through the wall of the forward cylinder member and opening into the forward end of the bore 5 by means of ports 69. The rearward end of the return passages are closed by the flange 17.

The forward cylinder member is provided with one or more exhaust passages 71 drilled forwardly through its wall from the rearward end face of the cylinder member. These passages open into the intermediate portion of the bore 5 through ports 73 and for permitting escape of exhaust air to the atmosphere, the flange 17 is cut away at 75 to permit the air to pass into the interior of the sleeve 23 whence it finds its way to the atmosphere through one or more passages 77 and 79.

The forward end of the cylinder member 20 I provide with a chuck 81 which receives the shank of the drill steel, the latter being struck by the hammer bar 10 of the piston at the end of the forward stroke. The hammer bar fits the forward bore 11 of the cylinder 25 in a fluid tight manner but is of such length that when the piston moves rearwardly, the hammer bar withdraws from this portion and places the interior of the bore 5 in communication with the atmosphere by way of 30 the chamber 89 and passage 91.

When the piston is in the position shown by Fig. 1 air is admitted to the forward end of the bore 5 in front of the head 7 of the piston by way of the passage 61, the annular 35 grooves 57 and 59, the bore 6 and the ports and passages 63, 65, 67 and 69. At this time the rearward end of the bore 5 is connected to the atmosphere by way of the port 73, the passage 71 and ports 77 and 79 and under 40 these conditions the piston moves rearwardly. After the piston moves rearwardly far enough to close the passage 63, the supply of motive fluid to the forward end of the cylinder is cut off to trap motive fluid in said forward end, which trapped fluid works expansively until it is released by the head 7 overrunning the exhaust port 73 and by the hammer bar withdrawing from the portion 45 11. When the shank moves rearwardly past the groove 57, live air is trapped in the extreme rearward end of the bore 6 which acts to cushion the hammer and to increase the energy imparted to the piston during its forward stroke.

When the piston has moved rearwardly to the position illustrated by Fig. 3, the air which is constantly supplied the annular groove 59 is admitted to the rearward side 50 of the head 7 by way of the reduced diameter portion of the piston, which, aided by the continuous pressure on the rearward face of the shank, causes the piston to move forwardly. During the forward stroke, the air in 55 front of the head 7 exhausts through the

passages 91 and 71 to the atmosphere as heretofore described.

To improve the action of the hammer I provide a reservoir chamber in the form of one or more drill holes 93 in the wall of the forward cylinder member and in constant communication with the annular groove 59 by way of one or more passages 95. The purpose of the reservoir chamber is to make available a large volume of air for preventing wire drawing, which would otherwise take place, when air is admitted to the rearward side of the head 7 of the piston.

For further improving the action of the hammer, I provide one or more expansion 80 chambers 97 for the rearward end of the forward cylinder chamber, these expansion chambers like the return passages 67 and reservoirs 93 being drilled through the wall of the forward cylinder member and closed 85 by the flange 17. The expansion chambers communicate with the bore 3 at a point slightly forward of the rearward end of the stroke of the head 5 by means of ports 99.

It will be borne in mind that a piston of 90 the type shown reciprocates about eighteen hundred times per minute, in other words, starting with the piston in the position shown by Fig. 3, it moves forward and strikes a blow and returns to this position thirty times 95 in each second. It has been estimated that the greatest portion of the time necessary for a hammer piston to move forward, strike its blow, return and again start forward is consumed in reversing the piston at the end 100 of its rearward stroke and for this reason it is of advantage not only to keep up the mean effective pressure by means of expansion chambers but to so form them that they will aid the piston in its reversal. With the 105 present invention, after the piston closes the exhaust port 73 on its rearward stroke, the back pressure is relieved by causing the residual amount of air between the head 7 and the rearward end of the bore 5 to be compressed into the expansion chambers and the decrease in back pressure so caused allows the piston to move rearwardly more rapidly than would otherwise be the case. When the reduced portion 12 of the piston 110 establishes communication between the annular groove 59 and the rearward end of the large bore of the cylinder during the rearward movement of the piston, the motive fluid admitted into the bore flows into the 115 expansion chamber 97 during the time the port 99 is open but owing to the speed at which the piston is moving not enough is admitted to bring the pressure up to that of the line before the head closes the port 99 by 120 its continued rearward movement. After the port 99 is closed, the head 7 of the piston is exposed to air at line pressure, which is more effective to quickly stop and reverse 125 the piston than if the expansion chamber at 130

this time were open, because under such conditions, the air would first have to fill up the expansion chamber before line pressure would be available.

5 Although I have described one specific embodiment of my invention for illustrative purposes, it is to be understood that I am not limited thereby to its particular details and that extensive deviations from the same 10 may be made without departing from the spirit of my invention.

Claims:

1. In a percussive tool, a cylinder and a piston presenting opposed pressure surfaces, 15 means providing a chamber communicating with said cylinder adjacent its pressure surface and adapted to be closed from communication with said cylinder by said piston at the end of its stroke, and means providing 20 for preadmission of motive fluid between said opposed surfaces before closure of said chamber and for cutting off of motive fluid after said chamber is again opened.

2. In a percussive tool, a cylinder and a piston 25 presenting opposed pressure surfaces, means providing a chamber communicating with said cylinder adjacent its pressure surface and adapted to be closed from communication with said cylinder by said piston at 30 the end of its stroke, an exhaust conduit for the space between said surfaces, means for interrupting the flow through said exhaust conduit, and means other than said chamber 35 for admitting motive fluid between said surfaces after closure of said conduit and before the closure of said chamber and for continuing such admission after closure of said chamber.

3. In a percussive tool, a cylinder and a piston 40 presenting opposed pressure surfaces, means providing a chamber communicating with said cylinder adjacent its pressure surface and adapted to be closed from communication with said cylinder by said piston at 45 the end of its stroke, exhaust and admission means for the space between said opposed surfaces, means controlling said admission and 50 exhaust means and providing a point of admission subsequent to the point of compression and prior to the closure of said chamber and a point of cut-off prior to the point of release and subsequent to the reopening of said chamber.

4. In a percussive tool, a cylinder having a 55 forward chamber and a rearward chamber of smaller diameter than said forward chamber, a piston having a head fitting said forward chamber and a shank having a reduced portion adjacent its forward end fitting said 60 rearward chamber, a reservoir chamber opening into said forward chamber at such a position that said head closes communication between said reservoir chamber and said forward chamber at the rearward end of the 65 travel of said head, and a pressure port com-

municating with the forward portion of said rearward chamber and positioned to be placed in communication with said forward chamber by said reduced portion at the rearward end of the piston stroke.

5. In a percussive tool, a cylinder, a piston 70 therein, means providing a pressure chamber opening solely into said cylinder at a point intermediate the ends of the piston travel and providing for complete closure of said chamber when said piston is at one end of its stroke, valveless admission means providing for preadmission to said end of said cylinder whereby said chamber is charged with live 75 motive fluid for storage therein during the preadmission and admission period to said end of said cylinder and such stored motive fluid is supplied to said end of said cylinder during the expansion period at said end.

6. In a percussive tool, a cylinder having 80 a forward chamber and a rearward chamber of smaller diameter than said forward chamber, a piston having a head fitting said forward chamber and a shank having a reduced portion adjacent its forward end fitting said 85 rearward chamber, a chamber formed in the body of said cylinder and opening into said forward chamber through a port positioned to be closed by said head when at the rearward end of its stroke, means for exhausting 90 the rearward end of said forward chamber when said head is at the forward portion of its stroke, and ports and passages controlled by said reduced portion of said shank for admitting motive fluid to the rearward end of 95 said forward chamber during the rearward stroke after cessation of said exhaust and before said port is closed by said head and for continuing said admission after said head closes said port.

7. In a percussive tool, the combination 100 with a cylinder receiving a reciprocating piston and said piston having a pressure surface which in conjunction with a pressure surface of said cylinder forms an expandable chamber, of means for alternately admitting motive fluid to and exhausting it from said expandable chamber, a reservoir chamber communicating with said expandable chamber at such a position that communication between the two is interrupted by said piston when said pressure surface of said piston approaches its position corresponding to maximum contraction of said chamber, and means for admitting live motive fluid to said expandable chamber when said piston is at its position corresponding to maximum contraction of said expandable chamber.

8. In a percussive tool, the combination 110 with a cylinder receiving a reciprocating piston and said piston having a pressure surface which in conjunction with a pressure surface of said cylinder forms an expandable chamber, of means for alternately admitting motive fluid to and exhausting it from said 115

expansible chamber, a reservoir chamber communicating with said expansible chamber at such a position that communication between the two is interrupted by said piston when said pressure surface of said piston approaches its position corresponding to maximum contraction of said chamber, and said means for admitting and exhausting motive fluid providing for preadmission and compression for the fluid cycle for said expansible chamber while said reservoir chamber is in communication with said expansible chamber.

9. In a percussive tool, a cylinder, a piston in said cylinder forming in conjunction with said cylinder an expansible chamber, means for alternately admitting and exhausting motive fluid to said chamber, reservoir means for relieving the effects of pressure opposing contraction of said chamber, said means being inoperative when said piston reaches the position in which it reverses its direction of reciprocation, and means for admitting live motive fluid to said expansible chamber for reversing the direction of reciprocation of said piston before said first named means is rendered inoperative.

10. In a percussive tool, a cylinder, a piston reciprocably mounted in said cylinder, an admission port, said cylinder having formed therein a reservoir communicating solely with said port, and means responsive to motion of said piston for distributing the fluid from said port for causing the piston to reciprocate.

11. In a percussive tool, a cylinder, a piston reciprocably mounted in said cylinder, said piston having opposed pressure surfaces, means providing an annular chamber surrounding an intermediate portion of said piston, means for conducting motive fluid to said chamber, another chamber formed in said cylinder and communicating solely with said annular chamber, and means responsive to motion of said piston for distributing the fluid from said last named annular chamber for action alternately against the respective surfaces of said opposed surfaces for causing said piston to reciprocate.

12. In a percussive tool, a cylinder having a larger chamber and smaller chamber, a piston having a head fitting said larger chamber and a shank fitting said smaller chamber, a live air admission port opening through the wall of said cylinder into said smaller chamber and at the end thereof adjacent said larger chamber, means affording a reservoir communicating solely with said port, and means for admitting fluid by way of said port to said larger chamber.

13. In a percussive tool, a cylinder having a forward chamber and a smaller rearward chamber, a piston having a head fitting said forward chamber and a shank having a reduced portion near its juncture with said head

fitting said rearward chamber, an annular groove formed in the wall of said rearward chamber at the forward end thereof, means establishing uninterrupted communication between said groove and a source of motive fluid supply, and means affording a reservoir communicating solely with said groove.

14. In a percussive tool, a cylinder having a forward chamber and a smaller rearward chamber, a piston having a head fitting said forward chamber and shank fitting said smaller chamber, a pair of spaced annular grooves formed in the interior surface of the wall of the smaller chamber, a passage formed in the wall of the cylinder and intersecting said grooves, means for connecting a source of motive fluid to said passage, and a passage opening into said rearward chamber between said grooves and being controlled by said shank for admitting motive fluid by way of both annular grooves to the forward end of said larger chamber.

15. In a percussive tool, a cylinder having a forward chamber and a smaller rearward chamber, a piston having a head fitting said forward chamber and shank having a reduced portion adjacent its forward end fitting said smaller chamber, a pair of spaced annular grooves formed in the interior surface of the wall of the smaller chamber, both annular grooves being overrun by said shank when said piston is at the forward portion of its stroke, a passage formed in the wall of the cylinder and intersecting said grooves, means for connecting a source of motive fluid to said passage, a passage leading from an intermediate portion of said smaller chamber to the forward end of said forward chamber, whereby the end of said shank may cause admission of motive fluid by way of both annular grooves to one side of said head and said reduced portion of said shank may cause admission of motive fluid to the opposite side of said head by way of one annular groove.

16. In a percussive tool, a cylinder having a forward bore and a smaller rearward bore, a piston having a head fitting said forward bore and a shank having a reduced portion near its forward end fitting said smaller bore, a passage for connection to a source of motive fluid supply and having a port opening into the forward end of said smaller bore, conduit means for admitting motive fluid to the forward end of said forward bore and having a port opening into an intermediate portion of said smaller bore, and said ports being so disposed whereby they are placed in communication by said shank at the end of the forward stroke for conducting motive fluid to the forward end of said forward bore and such communication is interrupted by said shank at the end of the rearward stroke and whereby the first named port is placed by the reduced portion of said shank in communication with the rearward end of

said cylinder at the end of the rearward stroke and such communication is interrupted at the end of the forward stroke.

17. In a percussive tool, a cylinder member having a bore and a longitudinally extending fluid receiving passage formed in the wall thereof and opening through its end surface, a second cylinder member having a bore and received by the bore of said first named member, a flange carried by said second cylinder member closing said passage, a passage in said second cylinder member forwardly of said flange placing the bore of said second cylinder member in communication with said longitudinally extending passage, a piston in said cylinder, and means including said passages for reciprocating said piston.

18. In a percussive tool, a cylinder member having a bore and a longitudinally extended fluid receiving passage formed in the wall thereof and opening through its end surface, a second cylinder member having a bore and received by the bore of said first named member, a flange carried by said second cylinder member closing said passage, a piston having portions fitting said bores, and means for reciprocating said piston including a port controlled by said piston for admitting fluid to said passage.

19. In a percussive tool, a cylinder member having a bore and a passage opening through its end surface, said passage having ports communicating with said bore at opposite ends thereof, a second cylinder member having a bore and a shoulder and being inserted in the open end of said first named cylinder member whereby said shoulder closes the end of said passage, said second member having a passage for establishing communication between its bore and one of the ports of the first named passage, and a piston fitting said bores and opening and closing said second passage in its reciprocations.

In testimony whereof, I have signed my name to this specification.

GEORGE H. GILMAN.
